FIG. 4

UNITED STATES PATENT OFFICE

2,427,056

SLIDABLY MOUNTED TAPE LOOP FORMER

George G. Keyes, Chicago, Ill., assignor to Teletype Corporation, Chicago, Ill., a corporation of Delaware

Application April 23, 1945, Serial No. 589,900

7 Claims. (Cl. 178—17)

1

The present invention relates to printing telegraph apparatus and more particularly to tape controlling devices therefor.

The primary object of this invention is to provide a tape controlling device to preclude the breakage of a record tape in its passage between two telegraph units.

Another object of the present invention is to provide a tape controlling device which will minimize the creasing of a portion of record tape weakened by the "letters" or all-marking code combination perforations therein when the tape is depressed to form a depending loop intermediate two telegraph units.

In prior devices of this nature, one of which may be found in United States Patent No. 2,355,657 issued on August 15, 1944, to R. A. Lake, it was discovered that under certain conditions in the preparation of fully perforated tape, the tape would become so weakened by the "letters" or all-marking code combination that the tape would crease at these points when deflected downwardly by means of a tape deflector.

When the sensing unit of a telegraph transmitter is at rest or operating at a much slower speed than the perforator, the tape, by means of the tape deflector, forms a loop intermediate the units. As the tape loop increases in size, the lowermost portion thereof decreases in size, thus causing an increased strain on the surface of the tape, which is likely to cause creasing of the tape at this point. When a portion of the tape which has creased as afore-mentioned reaches the lowermost point of the loop, the increased strain may cause the structure of the tape to break at said central point of the loop and change the loop into a substantially V-shaped form. A break in the tape at the apex of the V-shaped loop becomes a fulcrum point for the tape being fed into the loop. The tape forming the right arm of the V-shaped loop may buckle inwardly against the tape forming the left arm of the V-shaped loop, thereby causing the tape to form an upwardly extending loop which increases in size as the tape is fed through the perforator. The tape forming this upwardly extending loop will raise the tape deflector out of guiding position, thereby removing the only means of controlling the tape intermediate the perforator and the sensing unit. Thus, the tape may come in contact with the moving elements above the level of the perforator, thereby mutilating the tape and destroying the intelligence recorded thereon.

2

Specifically, the present invention consists of a member, mounted pivotally on the punch block of the perforator, which has secured to it a right-angularly shaped bracket extending above and transverse to the tape. Mounted slidably in a vertical position on said bracket is a weighted member, curved at its lower extremity, which rides on the tape to depress it downwardly intermediate the perforator and the sensing unit.

10 A more complete understanding of the foregoing and other objects and features of the present invention may be had from the following description when taken in conjunction with the accompanying drawings, wherein like reference characters designate similar parts throughout the several views, and in which

Fig. 1 is a partial front elevational view of that portion of the printing telegraph apparatus, disclosed in the afore-mentioned patent, necessary to describe the present invention which is incorporated therein;

20 Fig. 2 is a partial view of the mechanism illustrated in Fig. 1, showing the present invention in its position when the tape is taut intermediate the perforator and the sensing unit;

25 Fig. 3 is a perspective view of the apparatus embodying the present invention, and

30 Fig. 4 is a portion of tape having a "letters" or all-marking code combination perforated therein.

Having reference to Figs. 1 and 2, the printing reperforator 11 and the sensing unit 12 are substantially the same as the printing reperforator 35 and sensing unit disclosed in the afore-mentioned patent, which is incorporated herein by reference. Since the unit under consideration is substantially the same as that disclosed in the above-identified patent, the description of that 40 mechanism to be set out hereinafter will be of a general nature and will be detailed only in the description of those features which will facilitate describing the present invention.

45 A punch block 13 is secured to the reperforator casting 14, which in turn is mounted removably upon the base casting 15. The punch block 13 is suitably slotted to receive a tape 16 which is perforated in predetermined code combination by the punch members (not shown) contained in the punch block 13. The tape 16 is fed through the punch block 13 by means of a feed sprocket (not shown) cooperating with feed holes in the tape 16 to advance it to the sensing unit 12 which transmits the message recorded in the tape 16. 55 The tape feed sprocket (not shown) is secured

to a shaft 17 (Fig. 3) which is suitably journaled in the punch block 13. Located at the extremity of the shaft 17 is a thumb-nut 18 for manually rotating the feed sprocket.

The sensing unit 12 is of the pivoted or traveling type which is adapted to sense every code perforation, recorded in a tape by the printing reperforator, without the necessity of stepping the perforated tape a plurality of feeding distances from the perforating unit into the transmitting or sensing unit. This pivoted sensing unit is described in detail in U. S. Patent 2,262,012, issued on November 11, 1941, to R. A. Lake and reference may be had to that patent for the details both in structure and mode of operation of the pivoted sensing unit. The transmitter or sensing unit comprises essentially a plurality of pins or fingers to sense the perforations in a tape, a member for feeding the tape through the transmitter having rectilinear motion imparted to it, and a cam drum for controlling the operation of the sensing elements and the tape feeding member.

The sensing unit 12 has a base casting 19, Fig. 1, which is mounted removably upon the base casting 15 of the apparatus. The casting 19 consists of a pair of parallel vertical sections interconnected by a relatively flat web portion. The leftward extremity of the flat portion of the casting 19 is formed with a vertical portion 21 which is channeled to serve as a journal for a shaft 22 and is slotted to provide a comb which serves to guide the vertical oscillations of the Y-levers 23, mounted pivotally on shaft 22, which support and operate the sensing pins 24. The rightward portion of the wall sections of the casting 19 support pivot studs 26, only one of which is shown, upon which the movable or pivoted portion of the sensing unit is secured. Specifically, the frames 27, only one of which is shown, are secured to the pivot studs 26. A plate 28 is carried by the pivotally mounted frame members 27 and carries a hinge post (not shown) upon which is hingedly supported a tape gate 29 which in conjunction with the plate 28 defines the passageway for the perforated tape through the transmitter. A spring latch 31 holds the tape gate 29 in cooperating relation with the plate 28. Both the plate 28 and the tape gate 29 are provided with a plurality of apertures which are in alignment when the tape gate 29 is in cooperative relation with the plate 28.

The apertures in the plate 28 receive the reduced upper portions of the sensing pins 24. There is provided a sensing pin or finger for each of the possible perforations appearing in a transverse row of perforations in the tape, plus an additional pin to be employed as a tape-out indicator.

The tape is fed through the transmitter in accordance with a rectilinear feeding movement precisely as has been described in great detail in the above-identified Patent No. 2,262,012 and illustrated in Figs. 9 and 12 thereof. In view of the detailed description of this tape feeding mechanism in the afore-mentioned patent, reference should be had to said patent for a complete understanding of both the structural details and the precise mode of operation of this rectilinearly operable feed mechanism. The rectilinear feeding mechanism engages the tape feed perforations in the tape 16 to advance the tape or the transmitter, depending upon the amount of tape intermediate the sensing unit 12 and the

75 punch block 13 and the position of said sensing unit.

The rectilinear feeding mechanism imparts a feeding stroke to the tape to feed the tape 5 through the transmitter, and so long as there is a tape loop or tape surplus between the printing reperforator and the tape transmitter the tape will be advanced in this manner; but when the tape is taut between the reperforator and the transmitter the operating movement of the pivotally mounted transmitter will be restrained in a counterclockwise direction because of the engagement of the rectilinear feeding mechanism with the taut tape and will result in the 10 clockwise movement of the transmitter frame about its pivots 26. This movement of the transmitter will continue so long as the tape 16 remains taut between the transmitter and the reperforator or until the last character has been 15 transmitted at which time the apparatus is stopped automatically, as described in the above-mentioned patent.

As may clearly be seen, the sensing unit 12 is pivoted to oscillate about a horizontal centerline; 20 that is, through a vertical plane. Moreover, unit 12 is adapted to oscillate in inverted pendulum manner about a center 26. This over center travel of the transmitter requires the inclined feed of the tape 16 through the perforating punch block 13 in order that there may be a substantially straight line feed of the tape 16 from the reperforator 11 into the transmitter 12 when the transmitter has assumed its maximum clockwise position; that is, in abutment with the punch block 13. The leftward or leading surface of the punch block 13 is bevelled, inclined to the vertical, to present a plane which is substantially parallel to the position of the transmitter frames 27 so that the plate 28 will be in alignment with 25 the leading surface of said punch block 13. Thus, the tape 16 may be fed in one continuous line from the reperforator 11 into the sensing unit 12 in this extreme position.

It is clear from the brief description of the 30 rectilinear feeding mechanism of the sensing unit, which has been pointed out above and which is defined in greater detail in the above-identified Patent No. 2,262,012, that the rectilinear feeding mechanism is normally in engagement with the tape, and it follows that if the printing reperforator 11 operates at a greater rate than the 35 operation of the sensing unit 12 thereby accumulating tape therebetween, the tape will push the transmitter in a counterclockwise direction, aided by gravity, about its pivots 26 until finally the transmitter has reached its extreme counterclockwise position; that is, in abutment with an adjustable limit stop 32. This adjustable stop 32 is 40 suitably secured to a substantially U-shaped frame member 33 which spans the sensing unit and is secured thereto by means of screws engaging the vertical wall sections of the casting 19.

A pair of tape supporting fingers 34, only one 45 of which is shown, are carried by the web portion of the frame 33 and extend forwardly of the transmitter unit toward the perforator unit, extending, when the transmitter is in its extreme counterclockwise position against the stop 32, between the spaces which intervene the first and second and fifth and sixth tape sensing fingers. The tape supporting fingers 34 by projecting through the tape sensing unit serve to support the tape and sustain the weight of the tape loop between the sensing unit 12 and the reperforator 11 preventing bending of the tape over the 50

plate 28 of the transmitter. Should the tape be supported by the sensing fingers 24 and the edge of the plate 28 and there be a substantially large tape loop intermediate the sensing unit 12 and the reperforator 11, it is possible for the weight of the tape to bend or substantially break the tape at the plate 28 and prevent the feed of the tape through the transmitter. The tape supporting fingers 34 which are provided obviate this danger.

Mounted pivotally on the punch block 13 by means of stud 36 is a substantially Z-shaped tape depressor, as seen in Fig. 2, supporting member 37. Also mounted pivotally on stud 36 and suitably secured to member 37 is a right-angularly shaped bracket 38 which, by means of rivets 39, slidably support the tape depressor 41. The lower extremity of the bracket 38 is bent upwardly to form a deflecting member 42 to deflect the tape 16 downwardly between the punch block 13 and the tape depressor 41.

As shown in Fig. 3, the tape depressor 41 is mounted slidably in a vertical direction by means of the rivets 39 cooperating with a vertical slot 43 in the tape depressor 41. The lower extremity of the tape depressor 41 is rounded to form a pocket 44 which carries a cylindrical member 46 therein acting as an additional weight to assist gravity in urging the tape depressor 41 downwardly to its lowermost position, thereby depressing the tape downwardly to form a depending loop intermediate the reperforator and sensing unit, as shown in Fig. 1. A storage container may receive the tape as it accumulates between the units. The additional weight of the member 46 is not sufficient to cause the tape depressor 41 to break the tape 16 when the tape becomes taut between the perforator and sensing unit, at which time the tape will raise the depressor 41 to its uppermost position, as seen in Fig. 2. The extreme position of the depressor 41, Fig. 3, is limited to the length of the slot 43 and the placement of the rivets 39 on the bracket 38. Extending outwardly from the depressor 41, directly above the rounded lower extremity thereon and bent at a right angle so that its face is in a plane parallel with the edge of the tape, is a camming member 47, the operation of which will be described in detail hereinafter.

It may be seen in the accompanying drawings that the tape depressor supporting member 37 normally tends to rotate in a counterclockwise direction to an operating position under the influence of gravity, and, if desired, a biasing spring (not shown). A pin or handle 48 extending outwardly from the rightward or U-shaped portion of the member 37, shown more clearly in Fig. 3, is provided to manually rotate the tape depressor in a clockwise direction to an unoperative position; that is, out of the path of the tape 16 as it emerges from the code perforating punch block 13. The tape depressor may be rendered unoperative in this manner when it is necessary to thread the tape, initially through the transmitter.

Located at the extremity of the member 37 furthest from the stud 36 is a notch 49 which serves to engage the plate 28 of the sensing unit 12 when the sensing unit is in its extreme counterclockwise position, as illustrated in Fig. 1, and to render the transmitter immovable with respect to the punch block 13 as long as there is a sufficiently large tape loop intermediate the sensing unit 12 and reperforator 11.

As may be seen in Fig. 4, when the "letters" or all-marking code combination perforations are

recorded on the tape 16, as shown at 51, the tape is substantially weakened due to the amount of material removed from that transverse section of the tape. When the "letters" or all-marking code combination 51 is recorded in the tape in certain positions relative to the other code perforations which have only one perforation in their transverse sections, the tape is weakened considerably due to the marked difference in cross-sectional strength of the tape at these points, thus making the tape susceptible to creasing at said weakest point.

A brief description of the passage of the tape from the reperforator to the sensing unit under different conditions will now be given to illustrate more clearly the function of the tape depressor.

Assume the sensing unit 12 to be locked in its maximum counterclockwise position by the member 37 through the notch 49, as shown in Fig. 1, and the reperforator operating at a greater speed than the sensing unit. The tape 16 emerges from the punch block 13 and is depressed by the tape depressor 41 to form a depending loop intermediate the two units. The tape depressor 41 rides on the tape until it reaches its lowermost position as shown in Fig. 1.

As the tape 16 is fed from the punch block 13, in a step by step manner, its forward motion in 30 raises the slidable tape depressor 41. When the forward motion of the tape 16 is stopped, the tape depressor 41 depresses the tape to form it into a depending loop intermediate the reperforator and sensing unit. Thus, it may be seen that 35 the tape depressor 41 will bob up and down as it gradually drops to its lowermost position. By means of the yield created by mounting the tape depressor 41 slidable on the bracket 38, there is no sudden increase of strain on the tape 16 as 40 the tape is formed into a gradually increasingly smaller curve to form the right arm of the depending tape loop intermediate the reperforator and sensing unit, thereby minimizing the possibility of creasing the tape as afore-mentioned.

When the tape depressor 41 is in its lowermost position, the tape 16 follows a path substantially as shown in Fig. 1, curving downwardly and sliding along the back of the lower portion of the tape depressor 41 to extend the depending loop of tape as shown in dotted line position 52 in Fig. 1. If the sensing unit 12 is not operating, the tape 16 is extended downwardly into the depending loop to enter a storage receptacle (not shown) wherein it is stored until such time that 55 the message recorded on the tape is to be transmitted.

Assuming now that the speed of the sensing unit has been increased so that it is operating faster than the reperforator, the depending loop of tape intermediate the two units will decrease in size until the tape is taut between the sensing unit 12 and the reperforator 11, thereby raising the tape depressor 41 to its uppermost position and rotating it clockwise until the notch 49 of supporting member 37 is out of engagement with the plate 28 of the sensing unit 12, as shown in Fig. 2. The operating movement of the transmitter is restrained in a counterclockwise direction because of the engagement of the rectilinear feeding mechanism with the taut tape and will result in the clockwise movement of the transmitter frame about its pivots 26. As the sensing unit 12 is pivoting in a clockwise direction the rightward edge of the plate 28 engages the camming periphery of the supporting member 37 to

cam it upwardly. As the sensing unit 12 continues to advance toward the punch block 13, the plate 28 also engages the camming periphery of the camming member 47, which is in alignment with the camming periphery of the supporting member 37 when the tape depressor is in its uppermost position, Fig. 2, thereby rotating the camming member 47 and the supporting member 37 in a clockwise direction until they are both resting on the upper surface of the plate 28 when the sensing unit 12 abuts the punch block 13. As may be seen in Figs. 2 and 3, when the camming member 47 is rotated in a clockwise direction, the tape depressor 41 is raised out of engagement with the tape 16. A switch (not shown) is provided to interrupt the operation of the sensing unit 12 when it comes into abutment with the punch block 13, as previously mentioned.

Although a specific embodiment of the invention has been disclosed in the drawings and described in the specification, it is to be understood that the invention is not limited to such specific embodiment but may be modified and rearranged without departing from the spirit and scope of the invention.

What is claimed is:

1. In a device for forming a loop of tape, a first tape guide, a second tape guide, a pivoted supporting member mounted on said first tape guide, a bracket secured to said supporting member, and a slidible element supported on said bracket directly over the tape intermediate said guides, whereby said element is adapted to act under the influence of gravity to depress said tape to form a loop therein.

2. In a device for forming a loop of tape, a pivoted supporting member secured to a unit having a tape advancing means and biased in a manner whereby its extremity rests on a second unit having a tape advancing means, a bracket secured on said supporting member, and a weighted member mounted slidably on said bracket directly over the tape intermediate said units, said element acting under the influence of gravity, to depress said tape to form a loop therein.

3. In a telegraph apparatus, the combination of a recording mechanism to record indicia on a strip, a record sensing mechanism to sense the strip; said sensing mechanism being in juxtaposition with said indicia recording mechanism and movable relative thereto, a member mounted pivotally on said recording mechanism, a bracket secured to said pivoted member, and a weighted element mounted slidably on said bracket directly over said strip intermediate said recording mechanism and said sensing mechanism, said element acting under the influence of gravity to depress said strip to form a loop therein and said pivoted member operable to render said sensing mechanism immovable with respect to said recording mechanism when the tape loop is greater than a predetermined size.

4. In a telegraph apparatus, means to record characters on a tape, means to sense recorded characters, said recording and sensing means being in juxtaposed relation and movable with respect to one another, means including a slidible weighted instrumentality to direct the tape into a loop form intermediate the recording and sensing means and blocking means to render said recording and sensing means immovable with respect to one another when said loop has exceeded

a predetermined size, said tape directing means being operated by the tape when the loop is less than a predetermined size to render said recording and sensing mechanisms movable with respect to one another.

5. A telegraph apparatus comprising a recording mechanism to record messages on a tape, a sensing mechanism to sense recorded messages, said mechanisms being in juxtaposed relation and movable with respect to one another, a blocking member mounted on one of said mechanisms, and a slidible weighted member secured to said blocking member to direct the tape into a loop between said mechanisms whereby said blocking member is movable into blocking relation with said mechanisms when the loop exceeds a predetermined size and movable out of blocking relation with said mechanisms when the loop is less than a predetermined size.

20 6. A telegraph apparatus comprising a recording mechanism to record messages on a tape, a sensing mechanism to sense recorded messages, said mechanisms being in juxtaposed relation and movable with respect to one another, a blocking member mounted on one of said mechanisms, and a slidible weighted member secured to said blocking member in engagement with said tape and adapted to direct said tape into a loop between said mechanisms whereby said blocking member is movable into blocking relation with said mechanisms when the loop exceeds a predetermined size, said slidible weighted member being operated by the tape when the loop is less than a predetermined size to move said blocking member out of blocking position and to render said recording and sensing mechanisms movable with respect to each other, whereby one of said mechanisms engages said slidible weighted member to move it out of engagement with said tape.

40 7. In a telegraph apparatus, in combination a recording mechanism to record indicia on a strip, a record sensing mechanism being in juxtaposition with said indicia recording mechanism and movable relative thereto, a member mounted pivotally on said recording mechanism, a bracket secured to said pivoted member, and a weighted element mounted slidably on said bracket directly over said strip intermediate said recording mechanism and said sensing mechanism, said element acting under the influence of gravity to depress said strip to form a loop therein, said pivoted member operable to render said sensing mechanism immovable with respect to said recording mechanism when the tape loop is greater than a predetermined size, said weighted element being operated by the tape when the loop is less than a predetermined size to move said blocking member out of blocking position and to render said sensing mechanism movable with respect to the recording mechanism, whereby the tape table of the sensing mechanism cooperates with the camming peripheries of the pivoted member and the extension arm of the weighted element which are in alignment when said weighted element is in its uppermost position to rotate said pivoted member and weighted element until they are resting on the upper surface of said tape table of said sensing mechanism and thereby causing said weighted element to be out of engagement with said tape.

GEORGE G. KEYES.
